EMILE BRACQ, OF PAS DE CALAIS, FRANCE

FURNACE FOR ROASTING SULPHIDE AND OTHER ORES

Application filed February 11, 1926, Serial No. 87,726, and in France March 9, 1925.

This invention relates to improvements in helical hearth furnaces or furnaces having superimposed hearths, for roasting sulphide and other ores.

1. The arrangement is characterized by a central chamber of large dimensions. The hearths are thus easily accessible from within in the furnace. Moreover, the operations of carrying out the process with the aid of inner windows or inspection openings, cooling the scrapers by natural means and rapidly replacing damaged elements may be carried out from within the furnace. In this arrangement all the actuating mechanism is supported on a central rotating platform and is disposed in circulated air facilitating its operation. Thus the scrapers only are subjected to the action of the inner heat of combustion of the ores whereas all the other elements such as scraper holders and the like are protected therefrom.

The essential features of the above-mentioned arrangement are as follows:

2. 1. A central column through which, if necessary, cooling air may be supplied in a practical way to the scrapers and their holders which are guided on the said column and are designed for the rapid mounting and taking down of the scrapers.

2. The interior of the annular hearths is screened so as to allow easy inspection of the whole hearth by opening one inspection hole rotating with a central platform, the said opening allowing any point of the hearth, as far as the periphery, to be reached for stirring and upkeep purposes;

The material is divided and pushed in angular segments by new means. For helical hearths, these new means are characterized in that the operating and position-determining nut member is not vertically reciprocated for dividing the ore, as is the case in other helical-hearth furnaces. Moreover, the scrapers and their supports are balanced independently of the supporting platform, their operating mechanism and of the central chamber turning helically at the same time.

In the accompanying drawing:

3. Figure 1 is a sectional diametral elevation

of an improved furnace according to the present invention;

Figure 2 is a sectional plan view, taken half way up, of the furnace showing the operating parts for the individual movements of the stirring arms, which parts are disposed in the central rotating chamber.

Figure 3 is an elevation in part section and to a larger scale showing the method of obtaining a particular obturation of the interior of the hearths;

Figure 4 is a side elevation of one of the carriers for the arms and

Figure 5 is a plan of the central portion partly in section.

The annular helical hearth 1 made of refractory material is surrounded by a sheet-metal housing 2, the whole structure being supported on iron pillars 3 and 4. Joists 5 are carried on the said structure and are provided with pulleys 6 over which passes the cable attached to the scraper holders through the medium of the ball bearing 7, a counter-weight 8 being attached to the other end of the said rope. The floor within the central chamber is the platform 9 carrying the mechanism hereinafter described and the sectional-iron uprights 10 to which ring members 11 are secured. The uprights 10 are braced at the top by cross-ties 67 supporting a centrally disposed guiding sleeve 12 in which the tube 13 is adapted to slide. The central cylindrical chamber thus formed is also guided at its base by the platform which bears on the column 14 and on the base column 15 provided with helical groove 16 and firmly secured to the ground.

An operating nut member 17 is bolted to the platform 9, the threads of the said nut engaging the helical groove 16. The pitch of these threads and grooves is equal to the distance between the hearths 1. The underside of the platform 9 is provided with teeth 18 laid on a surface inclined to the pitch of the helix. These teeth are in mesh with a toothed wheel 19 rotated by the shaft 20 one end of which carries the pulleys 21 and 22 for rotation in both directions. The platform 9 is thus rotated by the toothed wheel 19 together with the nut member 17 which

causes the said platform to rise and sink while following a helical trajectory having the pitch of the groove 16.

In these circumstances all the movable parts together with the scraper holders 40 rise and sink following a helical movement at the same rate as the nut member 17, the pitch of which is necessarily that of the refractory hearths.

10 A clutch device co-operating with the belts of the pulleys 21 and 22 causes the shaft 20 to reverse at suitable times so that the direction of rotation of the platform 9 and the mechanical lay-out carried thereon is reversed and moves helically the other way.

Other operations now to be described, take place uninterruptedly while the platform 9 is angularly reciprocated. A horizontal shaft 24 is mounted in bearings 25 on the platform 9 and carries a helically toothed wheel 26, an eccentric disc 27 actuating the connecting rod 28, and a crank disc 29 actuating a connecting rod 30. 20 The shaft 24 is rotated by the worm 31 driven by the shaft 32 suitably connected to an electric motor 33 attached to the platform 9. The eccentric disc 27 and the crank disc 29 are therefore rotated through the medium of the helically toothed wheel 26, the result being the two following movements.

The pin secured to one end of the connecting rod 28 engages a recess 48 of an oscillator 34 pivoted to a fixed point 35 of a vertical support 36. The other end of the oscillator is attached to the pins 37 of a collar 38 adapted to rotate around the member 39 connected to the scraper holders 40. The connecting rod 28 is raised and lowered by the eccentric disc 27 so that the oscillator causes the holders 40, and therefore the scrapers 41 working in the furnace proper, to rise and drop continuously to the same extent. The lower portion of the member 39 has a circular extension integral with four stout ribs 42 engaging a collar 43 moved angularly as hereunder described.

45 The crank disc 29 actuates the connecting rod 30 through the medium of a trunnion 68, the other end of the said rod being connected to a crosshead 30° moving in a guide 44. The cross-head carries a pin 45 engaging a small slide 46 guided in the end of the collar 43 which is thus reciprocated by means of the crank disc 29 and the connecting rod 30. The amplitude of the movement of the said collar corresponds to the position of the trunnion 68 on the crank disc 29. This collar moreover angularly moves the holders 40, and consequently the scrapers 41 in the furnace proper, through the medium of the member 39 having four stout ribs engaging grooves 47 cut in the said collar 43.

55 The scrapers 41 working in the furnace proper are therefore vertically reciprocated

and angularly moved, the two movements combined causing the scrapers to move in an ellipse, the material on the hearths being divided in sections having this shape. While the above-described two movements are performed the platform rises owing to its rotation and follows the hearths until the clutch or change-over mechanism reverses the pulleys 21 and 22 for lowering the platform to its starting point, whereafter it is raised again.

70 While the platform 9 is sinking, the rise and drop of the holders 40 and scrapers 41 is discontinued as follows: In the operative stage the pin at the end of the connecting rod 28 engages a recess 48 at the end of the oscillator 34 and is held in that recess by a link 49. A lever 50 is pivoted to a fixed point 51 and is operatively connected to a non-fixed lever 53 through links 52. The last-mentioned lever takes bearing on a shaft 54 carrying a movable weighted lever 55 the lower end of which is provided with driving dogs adapted to co-operate with other dogs disposed at the lower end of the lever 53. 75 A vertical shaft 56 rotates a toothed wheel 57 meshing with a bevel wheel 58 keyed to the shaft 54 to which the weighted lever 55 is likewise secured. The other end of the shaft 56 carries an arm 59 the end of which is disposed abutment 60. When bearing on the said abutment, the arm 59 moves angularly and actuates the gear-wheels 57, 58 and the weighted lever 55 which then tilts over and actuates by means of its dogs the non-fixed lever 53 which in turn operates the connecting rod 28 through the linkwork. The end of the said connecting rod is thus moved into a cut-out portion 61 of the oscillator 34 and the pin on the connecting rod 28 leaves the recess 48 to move idly in the said cut-out portion 61. From that time the oscillator remains motionless until the lever 59 is again operated by an abutment and by reversing the mechanism moves again the end of the connecting rod 28 to the recess 48 of the oscillator 34 which is now again operated by the said connecting rod. Thus by virtue of the above arrangement the vertical reciprocation of the oscillator 34 actuating the holders 40 and the scrapers 41 is discontinued at the desired time.

80 The weight of the moving elements is divided in two, each weight portion comprising a separately balanced set of elements. The first such set comprises the platform carrying the lower actuating mechanisms and the metal framework supporting cast iron ring members for closing off the hearths. The second set comprises the holders 40, the scrapers 41, the rotating collar 38, the member 39 (which transmits the movement of the connecting rod 28 to the holders 40 and the scrapers 41), the connecting rod 30 and the collar 43. This 85

set is separately balanced by a cable passing over the pulley 6 and provided with a counter-weight 8 at its end.

The above-mentioned first set is balanced as follows. The flange of the nut member 17 rigidly secured to the platform 9 bears on a support 62 loosely surrounding the said nut member and having two arms 63 to the end of which cables 64 are attached which 10 pass over pulleys 65 and on which counter-weights 66 are hanging. As a consequence, the threads of the nut member 17 are relieved from any stress, the said member only guiding the platform 9 vertically. In furnaces hitherto known the nut member carried the rotating collar of the tilter on the outside and performed the duty of transmitting to the central shaft the vertical reciprocation imparted by the tilter. This involved 15 a marked wear on the inner threads of the nut member, leading to irregular working due to the stresses being transmitted through the edges of the steeply inclined threads. In the new arrangement the nut member is not 20 vertically reciprocated and has as its sole object to guide a perfectly balanced set of elements. The scrapers 41 and their holders 25 are separately balanced, the balancing being as accurate as possible so that the only 30 duty to be performed by the machinery is that of the scrapers 41 dealing with the material.

Suitably shaped ring members 11 are carried on sectional iron uprights 10 supported 25 on the platform 9. These rings face the refractory hearths 1 and are protected from the heat of the furnace. They are also cooled to an extent by the air circulating in the central chamber of the furnace. These ring members 30 11 are shaped so that they may be fitted with sheet-iron or cast-iron screens 69 inwardly lined with asbestos sheets 70 and 71 insulating the heat of the furnace proper. These screens are entirely gas-tight, as their upper 35 and lower edges lie in sand joints. In addition, they may also be covered externally with coarse heat-insulating material 72. One or more of these screens may be made to afford 40 passage to air into the furnace through vents 50 73 or suitably placed apertures. A whole hearth of the furnace is rendered visible by removing one of the screens or opening one of the apertures. Moreover incrustations 55 may be removed and stirring carried out at any point of the hearth as far as its periphery. This cannot be carried out normally 60 in any other type of mechanically worked roasting furnace. Easily removable and replaceable covers 74 prevent the gases from flowing anywhere but between the hearths.

Figures 4 and 5 illustrate the method of supplying fluid to the scrapers 41.

The air-blast may for example be led in through the base of the helically-grooved column 15, pass along the column 14 and issue

through ports 75 to reach the interior of the holders 40 from which it reaches the scrapers 41 through the pipe 76. The scraper 41 within the furnace proper is bolted to a slide 77 moving on guides 78 which are loosened when a scraper is to be placed in position or dismantled. In the latter case the slide 77 tightened to the guide 78 is slightly slackened and the scraper 41 may be bodily removed from the furnace before undoing the bolts whereby it is secured to the slide 77. Thus an unserviceable scraper may be replaced in a few minutes by a new one, the sliding closure 79 carried on the scraper 41 leaving a large free space, when removed, 75 for taking a scraper out, whatever its condition when dismantled. The essential feature of rapidly removing a scraper is inherent to the general arrangement of the furnace and is possible owing to the method of closing off the hearths of the furnace. 80

The scraper 41 being hollow and projecting out of the furnace proper, the heat of the said scraper may be naturally exchanged through the end 80 with that of the outer 90 surrounding air without the need of any artificially supplied cooling fluid. This feature is not to be found in any other furnace. Cooling may of course be intensified by circulating air or water or any other fluid 95 through the scraper holder, as hereinbefore described.

The lower end of the furnace is provided with a water, sand, or oil seal 81 efficiently preventing any air from entering the furnace 100 save through the right channels, a seal 82 of similar nature being provided at the upper portion to prevent the escape of sulphur gases.

I claim:

1. A furnace for roasting sulphurous and 105 other ores comprising in combination a helical hearth, a central vertically movable chamber, a crown wheel having the form of a toothed helical incline for vertically moving 110 said chamber, and means for operating said crown wheel.

2. A furnace for roasting sulphurous and 115 other ores, comprising in combination a helical hearth, a central vertically movable chamber, scrapers actuated by said chamber, means disposed within the central chamber 120 for forming the material under treatment into angular sections, and means disposed within the central chamber for advancing 125 said material, such means being actuated in the movement of said chamber.

3. A furnace for roasting sulphurous and 125 other ores comprising in combination a helical hearth, a central vertically movable cylindrical chamber, a central stationary column, scraper holders mounted thereon, means for imparting to said scraper holders a helical movement, said scraper holders in their helical movement turning and cutting

the material and means for imparting to said scrapers an independent vertical movement.

4. A furnace for roasting sulphurous and other ores comprising, in combination, a helical hearth, a central vertically movable chamber, a column having a helical groove, a nut member supporting the walls of the central chamber, a pinion for rotating said chamber, and agitating and cutting mechanism associated with the grooved column and said chamber, thereby transforming into a helicoidal movement the rotary movement effected by the driving pinion.

5. A furnace for roasting sulphurous and other ores comprising, in combination a helical hearth, a central vertically movable chamber, means for cutting the material under treatment, a balanced lever for transmitting motion to said cutting means, a column, an axial collar upon said column, trunnions upon said balanced lever, agitating arms actuated by said balanced lever, and means for producing an alternative vertical reciprocation of said agitating arms.

25 6. A furnace for roasting sulphurous and other ores, comprising in combination, a helical hearth, a central vertically movable chamber, rings upon said chamber, a frame supporting said rings, a driving platform supporting said frame, circular plates carried by said frame, said circular plates being covered with insulating sheets, orifices in said circular plates and valves closing said orifices.

35 7. A furnace for roasting sulphurous and other ores comprising, in combination, a helical hearth, a central vertically movable chamber, a central column, arm holders having hubs carried by said column, agitating arms carried by said arm holders and displaced laterally from the hub of said arm holders, a lateral slide, means fixing said arm holders to said lateral slide, said arms extending from said central chamber into said hearth.

45 8. A furnace for roasting sulphurous and other ores comprising, in combination a helical hearth, a central vertically movable chamber, counter weights balancing said central chamber in the movement thereof, a central column, arm holders carried by said central column, agitating arms mounted upon said arm carriers within said central chamber, a counter weight balancing said agitating arms and arm carriers in their alternative vertical reciprocating movements and means for operating said arms.

In testimony whereof I have signed my name to this specification.

EMILE BRACQ.
